COMBINATION DESK CALENDAR AND CARD INDEX TRAY OR FILE

Filed May 24, 1926

Inventor

James B Ormond
By Percy H Moore

UNITED STATES PATENT OFFICE.

JAMES B. ORMOND, OF FLAGSTAFF, ARIZONA.

COMBINATION DESK CALENDAR AND CARD-INDEX TRAY OR FILE.

Application filed May 24, 1926. Serial No. 111,357.

My invention relates to combination desk calendar and card index tray or file.

The primary object of my invention is to provide a tray, the cover of which can be readily detached or moved to open or closed position and which when open will be maintained in a vertical position at the back of the tray.

Another object is to provide the cover with a hinged closing flap for closing the end of the tray.

Other and further objects and advantages of my invention will be apparent as the specification is considered in connection with the accompanying drawings, in which:

Figure 1 is a front elevation of the tray showing the cover in open position;

Figure 2 is a section taken on the line 2—2 of Figure 1;

Figure 3 is a rear elevation of the tray with the cover in closed position;

Figure 4 is a section on the line 4—4 of Figure 3;

Figure 5 is a plan view of the end closure member;

Figure 6 is an end view of the tray illustrating a modified form of end closure member; and

Figure 7 is a fragmentary view of the tray wall 4 showing the slots 27 and 36.

Referring more particularly to the drawings wherein like reference numerals refer to corresponding parts throughout the views, 1 denotes a rectangular tray comprising side walls 2 front and rear end walls 3 and 4 respectively and a bottom 5. The rear wall 4 is formed at its upper edge with an inwardly and forwardly projecting flange 6 which rests upon and is suitably secured to partition 7, the latter being slightly spaced from the rear wall 4.

Resting upon the ledges or raised portions 8 at each side of the bottom 5 are three sets of cards 17 arranged in the order mentioned, first the daily calendar cards 9, the tabs 10 of which are numbered from 1 to 31 inclusive, second the monthly cards 11, the tabs 12 of which bear the months January to December inclusive and third the alphabetical cards 13, the tabs 14 of which bear the letters A to Z inclusive. These cards are supported in an inclined position against the usual follow block 15 mounted on the usual follow block rod 16, but this mechanism being of old and well

known construction, further description is deemed unnecessary. Reference however is made to my Patent No. 1,541,173, June 9, 1925, wherein this construction is illustrated and described in detail.

It will be noted that the front end of the tray 1 is normally open due to the fact that the front end wall 3 thereof is cut away to provide a half-elliptical opening 18. The cards 17 are thus normally exposed and accessible except when the top 19, about to be described, is in closed or Figure 4 position. When the top is in closed position as best illustrated in Figures 4 and 6, the opening 18 is closed by a closure flap 20, also about to be described.

The tray top or cover is formed with depending side flanges 21, the ends of the top being open, that is, the flanges do not extend across the ends. Projecting from the under face of the top or cover adjacent the rear end thereof are a pair of headed studs 22 which travel in a pair of correspondingly positioned vertical slots 23 formed in the rear end wall 4 of the tray, and a pair of short horizontally disposed slots 24 formed in the flange 6 of said rear end wall 4. The top edge of the partition 7, is notched or cut away as at 25, thus forming in conjunction with the slots 24, in effect, bayonet slots. A third headed stud 26 located on the face of the tray cover at approximately its medial point, engages in the short vertically disposed open-ended slot 27 in the rear end wall 4 and serves to maintain the top or cover in a vertical open position (see Figure 2) thereby permitting of the tray being handled or lifted from place to place without danger of displacing the top.

The flap or closure member 20 hereinbefore referred to is pivotally connected to or swung from the tray top 19 by means of a pair of hooks 28 engaging corresponding eyes 29 formed in an angle bar 40 in turn secured to the under face of the tray top. This member 20 which is preferably made of sheet material, is made in the form of a pocket by bending the edges of the semi-elliptical shaped back or body portion 30 first forwardly and thence inwardly thus providing what may be respectively termed a combined side and bottom wall 31 and a flange 32. The flange 32 being narrow and of uniform width as is true of the combined bottom and side walls 31, it follows that the

front of the flap or closure member is substantially open, thus exposing the calendar pad 33 which the member 20 is adapted to hold. The flange 32 is of just sufficient width to prevent the pad 33 from falling out of the flap or closure member, thus providing for a maximum of exposure, and the width of the combined bottom and side wall 31 is sufficient to accommodate a calendar pad of approximately one hundred pages, thus covering a period of many years. It will also be noted that the curvature and dimensions of the flap or closure 20 corresponds to the curvature and dimensions of the opening in the front wall 3 of the tray, to the end that when the cover or top 19 is moved to closed position the opening 18 will be completely filled or closed. During this operation of closing the tray top, the flap 20 swings by gravity into normal vertical position within the opening. The cover is then latched by means of the hook 34 and eye 35.

Assuming that the tray top is in closed position and the user desires access to the interior thereof, it is merely necessary to slide the cover rearwardly until the studs 22 reach the rear of the short horizontally disposed slots 24 in flange 6, whereupon the cover is tilted to vertical position and permitted to drop until the centrally disposed headed stud 26 drops into the short vertical slot 27. It will be understood that during this latter movement the cover is guided by the studs 22 traveling in the long vertical slots 23 also that the heads of the studs prevent displacement of the cover.

In closing the cover the reverse of the movement just described takes place. The stud 26 is elevated clear of the short slot 27, the flange 6 being cut away as at 36 adjacent the slot 27, to permit the head of the stud to pass. When the studs 22 have reached the top of the vertical slots 23, the cover is tilted downwardly and forwardly to horizontal position and at the same time moved slightly forwardly until the ends of the angle bar 40 on the bottom of the cover engage behind the front end wall 3, and prevent the cover from being displaced in a forwardly direction.

In Figure 6 a slightly modified form of flap 20 is illustrated. This modification differs from the preferred form in that the flap is of solid construction and is adapted to contain a clock 37.

What I claim as my invention is:

1. A desk calendar and card index tray comprising side, end and bottom walls, the front wall of the tray having an opening therein to normally render the cards in the tray visible and accessible, a cover for said tray and means swung from the inside of said cover for closing said opening when said cover is in closed position, and adapted to lie within said cover when said cover is in open position.

2. A desk calendar and card index tray comprising side, end and bottom walls and a cover, the front wall of the tray having an opening therein to normally render the cards in the tray visible and accessible, a closure member for said opening carried by said cover adapted to automatically swing to a position substantially parallel to the cover when the cover is in full open vertical position, and adapted to automatically swing to a position at right angles to said cover to close said opening when said cover is moved to full closed position.

3. A desk calendar and card index tray comprising side, end and bottom walls and a cover, said rear wall being provided with slots, headed studs on said cover adapted to engage in said slots and slidably and hingedly connect said cover to said tray.

4. A desk tray for containing calendar and index cards, the end of said tray having an opening therein, a cover for said tray carrying a closure for said opening, and means for slidably and pivotally connecting said cover to said tray whereby said cover may be moved to vertical position at the back of said tray, and a stud on said cover and a slot in the rear end of said tray for maintaining said cover in said vertical open position.

5. A desk calendar and card index tray comprising side, end and bottom walls, the front wall of the tray having an opening therein to normally render the cards in the tray visible and accessible, a cover for said tray and means swung from said cover for closing said opening when said cover is in closed position, said closure means being hollow and having an opening in its top and front face to respectively receive and expose to view a calendar pad.

In testimony whereof I affix my signature.

JAMES B. ORMOND.
